UNITED STATES PATENT OFFICE.

EUGENE B. CROCKER, OF PAWTUCKET, RHODE ISLAND.

DESIGN FOR AN EASEL.

SPECIFICATION forming part of Design No. 16,312, dated October 6, 1885.

Application filed August 21, 1885. Serial No. 175,012. Term of patent 7 years.

To all whom it may concern:

Be it known that I, EUGENE B. CROCKER, of Pawtucket, in the county of Providence and State of Rhode Island, have invented and produced a new and original Design for Easels, of which the following is a full, clear, and exact description, reference being had to the accompanying drawing, forming a part of this specification.

10 The figure represents the front elevation of my newly-designed easel.

The leading feature of my design consists in the upright standards or the rod-supports of the easel crossed near their upper ends, 15 and representing the stems and flowers of the cat-tail plant or flag.

The drawing shows the rods so arranged as to form the stems A, bearing the cat-tail ornaments *a* in a group of five. Of course the 20 number of these rods and the cat-tails may be

varied. The dotted lines represent a card, C, placed upon the easel.

The rods A, with their cylindrical enlargements representing the cat-tail or flag-plant, are grouped together so that the stems cross 25 each other near their upper ends, and the cylindrical enlargements *aa* form the ornamentation.

Having thus described my invention, I claim as new and desire to secure by Letters Patent— 3C

The design for an easel herein shown and described, the same consisting of the upright standards of an easel crossing each other near their upper ends, and representing the stems and flowers of the cat-tail plant or flag.

EUGENE B. CROCKER.
